UNITED STATES PATENT OFFICE.

MIKE DUBISH, OF CHICAGO, ILLINOIS.

DESIGN FOR A CURTAIN AND SHADE HANGER.

55,157.

Specification for Design.

Patented May 18, 1920.

Application filed September 25, 1919. Serial No. 326,398. Term of patent 3½ years.

To all whom it may concern:

Be it known that I, MIKE DUBISH, a citizen of Poland, and a resident of Chicago, in the county of Cook and State of Illinois, have invented a new, original, and ornamental Design for a Curtain and Shade Hanger, of which the following is a specification, reference being had to the accompanying drawing, forming part thereof.

The figure is a perspective view of a curtain and shade hanger, showing my new design.

I claim:—

The ornamental design for a curtain and shade hanger, as shown.

MIKE DUBISH.
